Primary Examiner — John R Yeh*(74) Attorney, Agent, or Firm* — Patterson Thuente Pedersen, P.A.(57) **CLAIM**

We claim the ornamental design for a grill scraper, as shown and described.

DESCRIPTION

FIG. 1 is a perspective view of our new design for a grill scraper;

FIG. 2 is a front view thereof;

FIG. 3 is a right side view thereof, the left side view being identical;

FIG. 4 is a top view thereof; and,

FIG. 5 is a bottom view thereof.

The broken lines in the drawings depict portions of grill scraper that form no part of the claimed design.
